UNITED STATES PATENT OFFICE.

SIDNEY W. B. RENOUE, OF PORTSMOUTH, ENGLAND.

FOUNTAIN-SHAVING-BRUSH.

1,244,894.

Specification of Letters Patent.

Patented Oct. 30, 1917.

Application filed July 11, 1916. Serial No. 108,743.

To all whom it may concern:

Be it known that I, SIDNEY W. B. RENOUE, a subject of the King of Great Britain, residing at Portsmouth, in the country of 5 England, have invented new and useful Improvements in Fountain-Shaving-Brushes, of which the following is a specification.

The present invention relates to brushes, and more particularly to that class there- 10 under known as fountain shaving brushes.

The primary object of the invention is the provision of a brush of the above stated character which will be simple in construction, durable in use, well adapted for the 15 purposes intended, and wherein a quick and easy feeding of the shaving liquid to the brush head is accomplished upon the manipulation of the brush casing.

A still further object of the invention is 20 the provision of a brush so designed to permit of the same being folded or inserted within the casing.

With the above and other objects in view, the invention consists in the novel features, 25 details of construction, and combination of parts which will hereinafter be more fully set forth, illustrated in the accompanying drawing and pointed out in the appended claims.

30 Figure 1 is a longitudinal sectional view; Fig. 2 is a view similar to Fig. 1, illustrating the brush locked in the casing for active use; and

35 Fig. 3 is a view of the brush removed from the casing, showing the brush head or bristles removed.

Referring more particularly to the accompanying drawing, in which like characters of reference refer to corresponding 40 parts in the several views, the brush generally is denoted by the reference character 5 embodying a hollow cylindrical casing 6 which may be constructed of any desired material, and having formed contiguous 45 with the lower end thereof an integrally bent annular flange 7 presenting the lower end of the casing with a circular opening 8, the purpose of which will be hereinafter more fully set forth. Mounted within the 50 casing 6 for reciprocating movements is the brush proper comprising a plunger rod 9 having a greater portion of its length exteriorly threaded, indicated at 10, while the forward end of the rod terminates in a nozzle 11 of conical form, and having a passage 12 for the admission of the liquid shaving

soap placed within said casing. Formed on the nozzle 11 at a point in advance of the inlet, 13 of the passage is a collar 14 upon the top face of which repose the extremities of the conical cluster of bristles or brush head 15. It will be noted from the drawing that the inner end of the brush head encircles the conical nozzle 11 and is secured thereto through the medium of a clamp 16. This 60 clamp 16 is of hollow tubular form interiorly formed with a frusto-conical socket 17 and the walls forming the socket at the smaller end thereof are flared outwardly to provide within the clamp an annular rib 18, 70 which, when the clamp is in applied position, is forced into clamping contact with the bristles, and thereby through the specific configuration of the nozzle and socket, establishes a permanent connection of the 75 brush head with said plunger rod. Mounted on the forward portion 10 of the plunger rod is a plunger 19 adapted to engage with the inner or under face of the collar 14 and upon which the lower end of the clamp 16 80 reposes, thus preventing any inward movement of the clamp, and serving as a seat therefor. This plunger 19 is secured in locked position through the medium of the locking disk 20. It will, of course, be un- 85 derstood that this plunger 19 may be constructed of any material, but preferably consists of a rubber disk. A boss 21 is threadedly mounted on the extreme inner end of the plunger rod 9 and is formed with 90 an exteriorly threaded sleeve 22 and a head 23. Mounted upon the collar 22 of the boss is a liquid feeding plunger 24 abutting with the inner face of the collar 23 and having its angular lip 25 frictionally engaging with 95 the inner circumference of the casing. This feed plunger 24 is retained upon the boss through the medium of the lock washer 26 threadedly engaged with the threaded sleeve 22 of the boss. I employ in connection with a brush of this character, improved means for locking the brush in the open end 27 of the casing comprising a 100 flexible band 28 which encircles the casing and has rigid thereto a locking dog 29 having an angularly bent locking tooth 30 which protrudes through an opening 31 formed in the forward end of the walls of the casing and engageable in the circumferential groove 32 of the clamp 16. 105

Assuming that the brush is folded or inserted within the casing when not in use,

better shown in Fig. 1 of the drawing, and it is desired to use said brush, the operator by inserting his fingers in the opening 8 of the casing will move the plunger in a direction 5 toward the open end 27 of the casing advancing the brush head 15 out of said casing, the locking band 28 is then slightly revolved to throw the locking dog 29 through the opening 31 and within the concentric groove 10 32 of the clamp. The brush in this form is thence presented for use. In order to supply a sufficient quantity of the liquid shaving soap, contained between the confronting faces of the fixed and movable plungers, rotation 15 is imparted to the casing 6 which forces liquid through the feed passage 12, and discharges the same within the bristles or brush heads 15. After this operation, the moistening of the brush will produce a shaving lather to be applied to the face of the user. After the completion of this operation and the use of the brush is no longer desired, the releasing of the gage or dog 29 and the striking of the lower end of the casing 20 against the palm of the hand of the operator, will slide the brush wholly within the casing and retain the same in a sanitary condition at all times.

From the foregoing description, taken in 30 connection with the accompanying drawing, the advantages of construction and of the method of operation will be readily apparent to those skilled in the art to which the invention relates, and while I have described 35 the principles of operation of the invention,

together with the device which I now consider to be the best embodiment thereof, I desire to have it understood that the device shown is merely illustrative, and that such changes may be made when desired as are 40 within the scope of the claims appended thereto.

I claim:

1. A device of the class described embodying a casing adapted to contain a quantity of 45 fluid, a plunger rod mounted in said casing for sliding movement having an exteriorly threaded portion, a nozzle formed at one end of the rod and having a feed passage, a brush head, a clamp for securing the brush head to said nozzle, and a plunger mounted on the threaded portion of the plunger rod and frictionally engaging with the inner circumference of the casing and operable upon 50 rotation of the casing to discharge the fluid 55 therein through the feed passage of the nozzle and into the brush head.

2. A device of the character set forth, comprising a casing adapted to contain a quantity of liquid, a brush slidably mounted within said casing, a plunger rod connected with the brush and provided with an inlet passage, a boss threadedly connected on said plunger rod at the inner end of said rod and at a point rearwardly of the inlet 60 opening, a plunger connected on said boss, and a locking washer threadedly mounted on said boss.

In testimony whereof I affix my signature.
SIDNEY W. B. RENOUE.
